UNITED STATES PATENT OFFICE.

HARRY G. SLINGLUFF, OF MOUNT VERNON, OHIO, ASSIGNOR TO PITTSBURGH PLATE GLASS COMPANY, A CORPORATION OF PENNSYLVANIA.

EDGE HOLDING AND FORMING DEVICE FOR SHEET-GLASS MACHINES.

Application filed June 5, 1923. Serial No. 643,496.

To all whom it may concern:

Be it known that I, HARRY G. SLINGLUFF, a citizen of the United States, and a resident of Mount Vernon, in the county of 5 Knox and State of Ohio, have made a new and useful invention in Improvements in Edge Holding and Forming Devices for Sheet-Glass Machines, of which the following is a specification.

10 The invention relates to apparatus for use with a sheet glass drawing machine. The invention has for its objects the provision of means for rendering the anchorage of the base of the sheet at its edge more secure, 15 and the provision of means for improving the edge of the sheet rendering it softer and free from roughness or cracks tending to cause breakage. Briefly stated, the first of these objects is accomplished by applying 20 chilling means preferably jets of air, to the glass bath at the points of anchorage, and the second object is accomplished by applying heat, preferably by means of gas flames, to the edges of the sheet immediately above 25 the stripping fingers. One embodiment of the invention is illustrated in the accompanying drawings wherein:

Figure 1 is a diagrammatic side elevation showing the drawing apparatus with which 30 the edge holding device is preferably used, such drawing device being shown and described in detail in my pending application Serial No. 621,184. Fig. 2 is a transverse section through one side of the drawing 35 tank showing the device in side elevation. Fig. 3 is an end elevation of the apparatus of Fig. 2. Fig. 4 is a perspective view of a part of the construction. And Fig. 5 is a view similar to that of Fig. 2 showing a 40 modification.

1 is the drawing tank or extension carrying a molten bath of glass 2 in communication with a suitable melting tank, not shown; 3 and 4 are endless belts, preferably 45 of asbestos fabric for continuously drawing the sheet of glass 5 from the molten bath; 6 and 7 are the driving pulleys for the belts, such belts being driven from a suitable motor, not shown; 8 and 9 are solid 50 steel bars circular in cross section lying in the lower ends of the belts and serving by reason of their weight to hold the belts in tension; 10 are a series of rolls back of the

inner flights of the belts for pressing the 55 belts against the glass, such rolls being yieldingly held inward by means of springs or weights, not shown; 11 and 12 are pairs of driven rolls covered with asbestos for assisting in the pulling of the sheet; and 13 is 60 one of the edge holding and forming devices to which the present invention is particularly directed, it being understood that such edge holding devices may be used in connection with any form of drawing mechanism, 65 although the one as illustrated and described is preferred.

It will be understood that an edge holding device, such as that shown in Fig. 2 is applied at each side of the sheet, but for brevity of description and illustration only 70 one of such devices is shown. The device in its preferred form consists of a plate 14 formed at its end into the stripping fingers 15 and having a pair of anchoring posts 16 which project downwardly into the glass as 75 indicated in Fig. 2. The plate at its rear end is secured to a rack bar 17 by means of the bracket 18 and the rack bar is mounted for longitudinal movement in the casing 19 and is moved in and out by means of a 80 pair of gears mounted on the shafts 20 and operated by means of a worm secured to the hand wheel 21, the purpose being to provide an in and out adjustment of the plate 14, and the adjusting means described being 85 that of a well known automobile jack. The casing 19 is secured by means of the bracket 22 to the vertically movable rack bar 23 mounted in the casing 24. This rack bar is 90 moved from the hand wheel 25 by means of mechanism corresponding to that above described for giving the horizontal movement of the rack bar 17. The casing 14 is mounted upon a suitable standard or base 25. By means of this construction, the 95 plate and the edge holding and forming devices carried thereby may be readily given adjustments in any desired direction in order to meet requirements.

The posts 16 serve to anchor the edge of 100 the sheet at its base and prevent inward movement thereof during the drawing action. Before positioning the tool, the posts are preferably heated, so that an immediate adherence of the glass thereto is secured. 105 In order to still further increase the viscos-

ity of the glass adjacent the posts so that the attachment may be more secure, provision is made for chilling the glass just behind the posts. This is accomplished by means of a pipe 26 secured to the plate 14 and connected to a suitable source of supply. The inner end of this pipe projects downwardly through the plate as indicated at 27 so that air is applied immediately behind the posts. The cooling as provided by this air supply serves to stiffen up the surface of the glass and promotes the attachment of the surface glass from the edge of the sheet to the posts and to the side wall of the furnace.

The fingers 15 are spaced apart as indicated in Fig. 4, so that their inner edges engage the sides of the tapering portion of the sheet and tend to thin it as it is drawn upward therethrough. In some periods of the operation these fingers may touch the glass only lightly or not at all, but in other periods the edges tend to draw too thick and at this time the fingers come into play to thin the sheet and maintain it at a uniform thickness. Under ordinary conditions the chilling effect of the device including the action of the metal upon the edge and the supply of air through the pipe 26 is such as to harden the edge of the sheet to too great a degree. This hardening tends to promote breakage and roughness due to the scraping action of the fingers 15 on the edge of the glass, and in order to remedy this condition heating means are provided just above the stripping fingers. These heating means are preferably in the form of a pair of gas burners 28 bent in the form indicated in Figs. 2 and 4, and provided with perforations 29 along their inner sides so as to direct the gas from the burners against the sides of the sheet at its edge. These burners are supplied by means of the pipe 30 secured to the plate 14.

Fig. 5 illustrates a modification in which the plate 31 provided with the fingers 32 corresponds in construction and function with the parts 14 and 15 of the Fig. 2 construction, the plate also being similarly supported for adjustment. In this construction, however, the posts 16 of Fig. 2 are omitted and in place thereof, the projection 33 on the clay guide bar 34 is substituted. This projection is brought up to or adjacent the surface of the glass and the base of the glass becomes anchored thereto, thus tending to prevent inward movement of the sheet in the same manner as the posts 16 of Fig. 2 prevent inward movement. Various other means might be employed for anchoring the edge of the sheet, and the configuration of the stripping fingers might also be changed to meet varying requirements. In some cases it may not be necessary to chill the surface

of the glass adjacent the anchoring means, or to heat the edge of the sheet above the fingers, but ordinarily I have found that these details of construction or their equivalent were necessary in order to secure a permanent anchorage of the edge of the sheet and in order to produce an edge which is uniformly smooth and soft. It will be apparent that the invention is not limited to chilling the surface of the glass by means of an air blast or to heating the edge of the sheet by means of gas burners, a variety of means being known in the art for accomplishing both these functions, although the devices employed are regarded as the simplest, cheapest, and most conveniently applied. It is possible to anchor the edge of the sheet directly to the wall of the furnace, in which case such wall constitutes the "means for anchoring the base of the sheet," but preferably the edge of the sheet is more remote from the wall of the furnace, as illustrated in Fig. 1, and other anchoring means, such as the posts 16 are employed between the furnace wall and the edge of the sheet. In order to regulate the temperature of the bath at the edge of the sheet, one of the posts 16 is preferably made hollow to receive the thermal couple 16^a connected by the wires 16^b to a suitable indicating device.

What I claim is:

1. In combination in apparatus for drawing a glass sheet from a molten bath, means for anchoring the base of the sheet in the bath at its edge, a pair of stripping fingers spaced apart above the base of the sheet so that they straddle said edge and thin it, and means for applying heat to the edge above the fingers.

2. In combination in apparatus for drawing a glass sheet from a molten bath, means for anchoring the base of the sheet in the bath at its edge, a pair of stripping fingers spaced apart above the base of the sheet so that they straddle said edge and thin it, means for chilling the glass adjacent the anchorage of its edge, and means for applying heat to the edge above the fingers.

3. In combination in apparatus for drawing a glass sheet from a molten bath, means for anchoring the base of the sheet in the bath at its edge, a pair of stripping fingers spaced apart above the base of the sheet so that they straddle said edge and thin it, means for directing a flow of air against the surface of the glass opposite the edge of the sheet, and means for applying heat to the edge above the fingers.

4. In combination in apparatus for drawing a glass sheet from a molten bath, means for anchoring the base of the sheet in the bath at its edge, a pair of stripping fingers spaced apart above the base of the sheet so that they straddle said edge and thin it, and

means for directing a flow of air against the surface of the glass bath opposite the edge of the sheet.

5. In combination in apparatus for drawing a glass sheet, means for anchoring the base comprising a post projecting down into the bath at its edge, a pair of stripping

members spaced apart above the base of the sheet, and temperature indicating means carried in said post.

10

In testimony whereof, I have hereunto subscribed my name this 25th day of May, 1923.

HARRY G. SLINGLUFF.
